UNITED STATES PATENT OFFICE

172,378

LOUNGE CHAIR

Pearl B. Bell, San Francisco, Calif.

Application July 1, 1952, Serial No. 20,438

Term of patent 14 years

(Cl. D15—8)

To all whom it may concern:

Be it known that I, Pearl B. Bell, a citizen of the United States of America and a resident of the city and county of San Francisco and State of California, have invented a new, original, and ornamental Design for a Lounge Chair, of which the following is a specification, reference being had to the accompanying drawing, forming part hereof, in which:

I claim:

The ornamental design for a lounge chair, substantially as shown.
